TANK

Harry L. Babcock, East Chicago, Ind., assignor to
 Graver Tank & Manufacturing Co., East Chicago, Ind., a corporation of Illinois

Application November 14, 1932, Serial No. 642,485

7 Claims. (Cl. 220—26)

This invention relates to storage tanks, such as are used for storing oil or gasoline, and has been illustrated as embodied in a floating roof type of tank. In the storage of gasoline and other volatile and combustible material, various problems arise. A fixed roof is unsatisfactory when the tank is only partially full, because a large vapor space is left above the gasoline which, of course, is unsafe on account of the danger of explosion, and because it must be completely self-sustaining. It is, therefore, preferred to use a floating roof which, by its nature, eliminates the major portion of the gas space by resting on the oil.

With floating roofs, however, there are the problems of sealing the edges so far as possible without materially affecting the movement of the roof, and without permitting the formation of a gas pocket of any considerable size in connection with the seal, and of minimizing the surface exposed for evaporation. According to the present invention, these problems are solved by constructing a floating roof similar in many respects to other floating roofs, but provided with a series of floats around and under the peripheral portion arranged to seal against the floating roof and the sides of the tank under the influence of their buoyancy, and so constructed as to minimize the presence of vapor pockets. In such a roof there would of course be the problem of inserting and replacing the floats, and this has been met by providing hatches of a special form. Such a roof involves also the problem of providing a seal to decrease evaporation and watersheds so that water striking on the floats will so far as possible drain onto the roof rather than into the tank. This problem has been met by providing special sealing members which overlap the sides of the floating roof, and each other, and which are so attached to the floats as to be readily accessible.

With these and various other objects in view, the invention may consist of certain novel features of construction and operation, as will be more fully described and particularly pointed out in the specification, drawings and claims appended hereto.

In the drawings, which illustrate an embodiment of the device, and wherein like reference characters are used to designate like parts,

Figure 1 is a plan view of a tank;

Figure 2 is a vertical cross-sectional view of the construction of Figure 1 built in accordance with this invention;

Figure 3 is a detail sectional view showing

particularly the construction of the float and its relation to the roof, and is a cross-section taken through the line 3—3 of Figure 4;

Figure 4 is a plan view of Figure 3;

Figure 5 is a cross section through the line 5—5 of Figure 6, and illustrates primarily the construction of the hatchway; and

Figure 6 is a plan view of the structure shown in Figure 5.

Although my invention may take many forms, only one has been chosen for illustration. In this form the central portion of the roof illustrated in Figure 1 is commonplace and has been shown simply for the purpose of illustration. The roof may comprise the deck bottom 10 suitably reinforced by beams 12 which may extend radially and also circumferentially of the deck. Preferably one of these beams or girders extends around the periphery of the deck bottom, as at 14. Suitable super-structure 16 may be provided for bracing the deck and maintaining it in the shape desired, so that water will properly flow from the periphery to the center or to such other drainage point as may be provided, from which it may be drained in any well known manner. Welded or otherwise secured around the periphery of the deck bottom 10 are the deck sides 20 which extend upwardly at a suitable angle, as will be described hereinafter. Beneath the deck side 20 are the floats 22 which press against the deck sides 20 and against the tank wall 24. At any convenient number of locations there may be provided suitable hatchways 26 for permitting the removal of the floats. Suitable means for draining and filling the tank are of course also provided, though for the sake of simplicity they have not been shown. Legs 28 have been indicated for supporting the roof as the oil is drained out from the tank, to prevent injury of the roof or the parts under it. Figure 2 illustrates the same structure in about the same scale, and therefore it gives a more clear arrangement of the various parts mentioned. It may be noted at this point that guides are usually provided for keeping the main portion 45 of the roof centered with respect to the tank, but these have been omitted for the sake of clarity.

Most of the novel details are shown best in Figures 3 to 6. In Figure 3 are shown the details of a float and its seal. The float is provided with a curved outer surface 32 which contacts the side of the tank and is curved enough to prevent the float from catching on outstanding rivets or joints between plates or other obstructions. The

outer surface may be provided with a contact plate 34 which preferably extends throughout the surface of the outer end 22, and if desired may be made of some non-corrosive metal, or may be coated or covered with a non-corrosive metal, such as brass. The top 36 of the float is formed at an angle corresponding to the angle of the deck side 20, and is preferably of the same shape, so as to contact therewith throughout the overlapping surfaces. At this position there is preferably provided a contact plate 38 coextensive with the top 36 and made of copper, brass, or other non-corrosive metal to avoid all danger due to rust forming between the top 36 and the deck side 20, and preventing their proper sliding action. This plate is preferably welded or otherwise secured to the top 36. The float itself may be made of any desired metal.

The angle of the deck side 20 is quite important, for if it is too steep, the floats 22 will not be properly thrust inwardly by downward movement of the roof when the float hits some obstruction. If the angle of the deck side 20 is too low, then the buoyancy of the float will not shove it outwardly against the tank wall 24. One angle that is found to be satisfactory is an angle of 35 degrees from the horizontal, but of course any angle close to that would probably be satisfactory, and experiment under particular conditions may show that angles which are quite different would be satisfactory so long as the inclination is at least as great as the critical angle for sliding under the influence of buoyancy alone. The critical angle means the angle below which the pontoons will not be slid by their buoyancy under the particular conditions of any given tank; the particular conditions including, for example, the qualities of the metal surfaces. In the claims the term "effective inclination of the sliding surfaces" has been used to cover the possibility that there may be only one inclined surface (if it was nevertheless effective as an inclined surface) and to exclude inclined surfaces which did not function as such. The deck side 20 is preferably made up of several strips butt-welded together to present a smooth under surface. The joints between these strips may be overlaid with extra strips of metal for the purpose of reinforcement and to insure perfect drainage if desired.

The side plate 34 of the floats extends upwardly above the float to provide a flange 40 thereabove. To each of these flanges is secured, preferably by bolts 42, a seal plate 44. This seal plate is arranged to extend over the deck side 20 and is preferably provided with a groove 46 into which may be inserted packing 48 to render the seal more water-tight. Both the packing 48 and the flanges forming the groove 46 may be omitted whenever necessary, as at the points where occur the joints in the deck side 20.

In order to protect the joints between the floats and the seals from leakage as much as possible, an overlap and seal strip 50 may be provided on each seal plate 44 preferably by welding. Such overlap seal strip extends across the space between the seal plates and sufficiently over the adjoining seal plate to secure a good drainage. The flange 40 of the adjoining float may be cut down to permit the free movement of the plate 50 relative to said float.

In order to permit the removal of the floats 22 the hatchways 26 are provided, as previously mentioned. These hatchways are best shown in

Figures 5 and 6, in which 54 designates the hatch proper. As illustrated therein, this hatch is secured to the deck side 20 by suitable screws 58 which may screw into a facing plate 58 welded to the deck side 20. A gasket of course may be provided if desired. In order to prevent flooding of the roof when the hatch 54 is opened, or in the event it should leak, the hatchway is formed with a water-tight housing 60 around the hatch 54, the sides and back of which may be welded to each other and to the deck. For the sake of simplicity, the seal plates have been omitted from Figures 5 and 6, but it should be understood that they would normally be used, and would be provided with slots for receiving the wall 60 and a suitable provision would be made to permit their sliding over the bolts 58 and the hatch 54.

The floats 22 may be placed in position through the hatchways 26 by opening the hatch 54. If it should be desired to remove any of the floats 22 the hatchway nearest to it can be opened and the successive floats removed, until the one desired is reached. In removing each float, it is only necessary to remove the seal plate 44 so that the float may be slid to the position of the hatchway and removed.

The operation of the structure hardly needs explanation. As the deck is raised or lowered by the change in the level of the oil, the floats 22 are likewise raised and lowered. In any given position the float 22 is pressed by its buoyancy against the deck side 20 and by its co-action with this deck side is pressed outwardly against the tank wall 24. When the deck is raised or lowered, if the float should strike a rivet or other projection it would slide the float inwardly along the deck side 20. As soon as the projection is passed, the buoyancy of the float and its reaction on deck side 20 thrusts the float outwardly and upwardly into its normal sealing position. With the structure shown, it is evident that both the surface exposed for evaporation and the volume of gas pockets has been reduced to a minimum, if the weight of the deck is such that it would sink sufficiently deeply to submerge the corner 64. The only surface exposed would be that between the floats 22 and that on the outside of the floats 22. These floats are located as close together as possible, so that the surface exposed between them would be extremely small. Likewise the curvature of the outside of the floats is such that except when a float is pressed in by a rivet or the like, the surface of the oil exposed on the outside of the float would also be quite small. Inasmuch as the air contacting with the surface in both places would normally be stagnant, the evaporation would be almost negligible. In commercial productions, it might of course often occur that the corner 64 would not be submerged, and so the exposed surface would be slightly greater but it would nevertheless be considerably less than in any former structure having the other advantages of this roof.

It is to be understood that many other embodiments of the invention, including some in improved form, will be apparent, and in the course of time more will be devised by those skilled in the art. It is not desired that this invention be limited to the details described, for its scope includes all such forms or improvements as come within the spirit of the following claims, construed as broadly as the prior art will permit.

What is claimed is:

1. The combination of a tank for the storage of oil and the like, and a floating roof therein; said floating roof including a deck having an upwardly

and outwardly extending peripheral portion which extends above the level of the oil, and a series of freely movable floats below said peripheral portion arranged to form a seal between the same and the wall of said tank; said peripheral portion having spaced hatchways formed therein for permitting the removal of said floats.

2. The combination of a tank for the storage of oil and the like, and a floating roof therein; said floating roof including a deck having an upwardly and outwardly extending peripheral portion which extends above the level of the oil, and a series of floats below said peripheral portion arranged to form a seal between the same and the wall of said tank; said peripheral portion having hatchways formed therein for permitting the removal of said floats; said hatchways including upwardly extending walls having water-tight joints with said deck and arranged to prevent the passage of liquid from said hatchway onto the main portion of said deck.

3. The combination of a tank for the storage of oil or the like; a vertically movable roof in said tank including a deck having a peripheral portion smaller than said tank; a series of floats beneath said peripheral portion pressing upwardly thereon, one of the contacting surfaces between each said float and said peripheral portion being so inclined as to react to said buoyancy and press said float outwardly against the wall of said tank; and a watershed extending from a point adjacent an upper and outer portion of each said floats downwardly and inwardly and over said peripheral portion.

4. The combination of a tank for the storage of oil or the like; a vertically movable roof in said tank including a deck having a peripheral portion smaller than said tank; a series of floats beneath said peripheral portion pressing upwardly thereon, one of the contacting surfaces between each said float and said peripheral portion being so inclined as to react to said buoyancy and press said float outwardly against the wall of said tank; and a watershed secured to an upper and outer portion of each said floats and extending downwardly and inwardly and over said peripheral portion.

5. The combination of a tank for the storage of oil or the like; a vertically movable roof in said tank including a deck having a peripheral por-

tion smaller than said tank; a series of floats beneath said peripheral portion pressing upwardly thereon, one of the contacting surfaces between each said float and said peripheral portion being so inclined as to react to said buoyancy and press said float outwardly against the wall of said tank; and a watershed secured to an upper and outer portion of each said float and extending downwardly and inwardly and over said peripheral portion, said watershed carrying a flexible sealing strip in contact with said peripheral portion.

6. The combination of a tank for the storage of oil or the like; a vertically movable roof in said tank including a deck having a peripheral portion slightly smaller than said tank; and a series of floats beneath said peripheral portion pressing upwardly thereon and having a sliding engagement therewith and with the wall of the tank; the wall engaging surface of each said float being so cam-shaped that when said float is raised or lowered against projections it will be pressed inwardly, the contacting surfaces between said floats and said peripheral portion being inclined at such angle that the buoyancy of the floats alone will be effective to cause them to slide outwardly and the inward thrust of said projections will be effective when the roof is lowered to slide said floats inwardly, said inclination being approximately thirty-five degrees.

7. The combination of a tank for the storage of oil or the like; a vertically movable roof in said tank including a deck having a peripheral portion slightly smaller than said tank; and a series of floats beneath said peripheral portion pressing upwardly thereon and having a sliding engagement therewith and with the wall of the tank; the wall engaging surface of each said float being so cam-shaped that when said float is raised or lowered against projections it will be pressed inwardly, the contacting surfaces between said floats and said peripheral portion being inclined at such angle that the buoyancy of the floats alone will be effective to cause them to slide outwardly and the inward thrust of said projections will be effective when the roof is lowered to slide said floats inwardly, said inclination being thirty-five degrees with substantial exactitude.

HARRY L. BABCOCK. 50
